UNITED STATES PATENT OFFICE

2,307,911

FLUID DISPENSING APPARATUS

Virgil D. Barker, Westfield, N. J.

Application June 18, 1940, Serial No. 341,122

8 Claims. (Cl. 221—73.5)

Although not limited to any particular embodiment, my invention may be advantageously embodied in apparatus for dispensing air at an automobile service station. At such a station, compressed air is principally used for operation of elevators to lift vehicles to permit them to be greased with facility; to dispense grease under pressure to the bearings of such vehicles, and to inflate the vehicle tires. It is ordinary practice to highly compress air, say to 150 pounds per square inch, by a pump operated by an electric motor, and to store it in a supply tank from which it may be released through dispensing apparatus which is adjustable to predetermine the pressure to which any air receiver may be charged.

Letters Patent of the United States No. 2,162,474 was granted June 13, 1939, to me for Fluid dispensing apparatus, of the class above contemplated and operative to dispense compressed air by a succession of pulsations until the back pressure through the dispensing conduit reaches that to which the controlling means is adjusted. That apparatus includes two control valves (shown in Fig. VI) each separately spring pressed toward its closed position but adapted to be automatically opened, by compressed air operating through lever linkages, to dispense the highly compressed air in such pulsations, through the dispensing conduit, until the selected pressure, variably predetermined by manual adjustment of a spring, is attained in the tire or other air receiver. In that patented structure, the two valves are operated in proper sequence by respective rocker cams, in cooperative relation with respective rocker cam levers, carrying respective rollers, which are independently spring stressed into cooperative relation with the rocker cams. My present invention is a modification of the construction, arrangement, and method of operation of that patented structure. Both inventions utilize two diaphragm chambers each containing a pressure sensitive reciprocating diaphragm, subjected to stresses in opposite directions by fluid pressure and a spring opposed to such pressure, both diaphragms being intermittently subjected to high pressure fluid from a reservoir or other source and one hereinafter termed the "second" chamber is continually in communication with a service conduit, through which the highly compressed air is dispensed, which conduit is normally, automatically, closed by a valve at its discharge end between successive dispensing operations; whereas the other chamber is not in communication with said conduit. In said patent, the diaphragm chamber which is not in com-

munication with the service conduit, and which is termed the "first" chamber, is continually in communication with the atmosphere through a restricted vent local to that chamber and remote from the control valves. On the contrary, in the present invention there are four automatically operative valves; there is no continually open vent to the atmosphere, but fluid is intermittently vented from the first diaphragm chamber by one of the control valves. Another valve controls the inlet of pressure to that chamber, and what is herein termed the main valve controls the supply of air directly from the source to said second chamber and service conduit, the passage of air to and from said second chamber being controlled by what I term a "timer" valve which automatically determines the times when the first and second valves shall be opened and closed, to alternately charge the first diaphragm chamber with the highest pressure air, and vent it to the atmosphere.

My invention operates in positively controlled cycles to force successive pulsatory charges of fluid into a receiver; each charge of fluid being automatically terminated at an interval after its initiation.

Only a small quantity of the high pressure fluid from the source is required to furnish sufficient power for operating the apparatus, and it is subsequently exhausted to the atmosphere by the automatic opening of said second valve.

My invention comprises the various novel features of construction, arrangement, and method of operation hereinafter more definitely specified.

In said drawing,

Fig. I is a rear elevation of a main casing, connected with a conduit leading from the high pressure fluid supply reservoir and with a fluid dispensing service conduit, and said casing encloses the two diaphragm chambers and has on the front thereof indicating mechanism, not shown herein, including a plurality of adjustable numbered wheels.

Fig. II is a longitudinal sectional view of the main valve casing shown in Fig. I and the valve therein which controls the supply of high pressure air to the second diaphragm chamber, and the service conduit.

Fig. III is a longitudinal sectional view of the timer valve shown in Fig. I.

In said drawing, the main casing 1, (which has the rear cover plate 1^a, partly omitted,) encloses two diaphragm chambers 2 and 3, each containing a reciprocating diaphragm, respectively 4 and 5. The fluid pressure supply conduit 6, from any

suitable source of highly compressed air, supplies such air to said diaphragm chambers under automatic valve control, as hereinafter described. The fluid pressure service conduit 8 leads from said chamber 3, and the compressed air is dispensed through it to the receiver. For the purpose of servicing and inflating automobile tires, said service conduit 8 may have a flexible dispensing hose 8¹ connected therewith having at the discharge end thereof a suitable connecting fitting or chuck 8² for convenient attachment to a tire valve stem 8³. Such a chuck embodies a valve which closes to prevent air from escaping from the hose when not attached to a tire stem, but is automatically opened and automatically unseats the tire valve when the chuck is properly applied to the tire valve stem.

Said diaphragm 5, which is subjected to the fluid pressure in said service conduit 8, has operatively connected therewith the reciprocating plunger 5'. The bell crank lever 11, which is fulcrumed on the shaft 12, between a pair of suitable bearings 13 in said casing 1, has its short arm 11' in cooperative relation with said plunger 5' and has its long arm 11'' connected with the right hand end of the spring 15. The left hand end of said spring 15 carries the nut 16 which is in threaded engagement with the adjusting screw 17 cut on the shaft 18 extending exterior to said casing 1 and provided with the crank handle 19 by which it may be adjusted. That is to say, the stress of said spring 15 may be increased by turning said crank 19 clockwise or decreased by turning it counterclockwise.

I find it convenient to connect with said shaft 18 indicating means for manifesting in pounds the pressure to which the receiver is to be charged, which is predetermined by the manual adjustment of said spring 15. Such means includes a gear pinion 21 on said shaft 18 and the intermediate gear 22 which meshes with the indicator mechanism gear 26.

When the crank handle 19 is turned by the operator, the gear 26 turns the indicating mechanism which, as disclosed in detail in my Patent No. 2,162,474 aforesaid, includes three wheels each having on its circumference a series of numbers from "1" to "9" and "0." The first of said wheels, which indicates individual pounds, is connected, by tens-transfer gearing, with the second numbered wheel, each of the numbers on which represents tens of pounds, and that second wheel is connected, by tens-transfer gearing, with the third numbered wheel, each of the numbers on which represents hundreds of pounds. That arrangement is such that upon a complete rotation of the successive numbered wheels of lower order, the wheel of the next higher order is turned one-tenth of a revolution. Consequently, when the operator turns the crank handle 19, the three numbered wheels indicate the pounds pressure to which the apparatus is set by the screw 17 stressing said spring 15 to move said bell crank lever 11. For instance, in the position shown, the screw 17 has been manually adjusted to insure dispensation of compressed air through the service conduit 8 until an automobile tire or other receiver is charged to a pressure of thirty-five pounds per square inch.

Said supply conduit 6 has two branches respectively 6^a and 6^b respectively leading to the diaphragm chambers 2 and 3; said branch 6^b being in direct communication with the service conduit 8 through the T-fitting 28 which forms the casing for the timer valve 28' shown in Fig. III.

The first, second, and third control valves above 75

contemplated are respectively included in the individual valve casings 29, 30, and 31, which are all of the same size and pattern, (best shown in Fig. II) and respectively indicated at 29', 30', and 31' in Fig. I, arranged to be normally respectively shut by their springs 29^a, 30^a, and 31^a and thrust open by respective rod stems 29^b, 30^b, and 31^b.

Said first valve 29' controls the supply of the high pressure air from the conduit 6 through the branch 6^a to the diaphragm chamber 2. Said second valve 30' controls the exhaust of air from the diaphragm chamber 2 backward through the branch 6^a to the valve casing 30 and thence through the exhaust vent 32 in that valve casing leading to the atmosphere. Said third valve 31', which is the main valve, controls the supply of high compressed air from the supply conduit 6 through the branch 6^b and timer valve casing 28 to both the second diaphragm chamber 3 and said service conduit 8.

As shown in Fig. I; the long arm 11'' of the bell crank lever 11 is arranged to push the valve 29' open by its stem 29^b when the diaphragm 5 is lifted by admission of high pressure air beneath it through the timer valve casing 28, but permits said valve 29' to be closed by its spring 29^a when the bell crank lever 11 is in the position shown in Fig. I to which it is stressed by its spring 15 when air pressure beneath the diaphragm 5 diminishes to less than the pressure for which said spring 15 is adjusted. In the position shown in Fig. I; the long arm 11'' of the bell crank lever 11, under stress of its spring 15, has thrust the valve 30' open by its stem 30^b, thus opening the valve casing 30 and air conduit branch 6^a to the atmosphere, through the exhaust vent 32 in the valve casing 30 to permit the escape of air from beneath the diaphragm 4 in chamber 2.

Said diaphragm 4, which is subjected to the fluid pressure in the chamber 2, has operatively connected therewith the reciprocating plunger 4'. The bell crank lever 34, which is fulcrumed on the shaft 35 between a pair of suitable bearings 36 in said casing 1, has its short arm 34' in cooperative relation with said plunger 4', and has its long arm 34'' connected with the left hand end of the spring 38, which has its right hand end anchored on the stop stud 39. The cam roller lever 40 is fulcrumed at its left hand end on the stud 41 carried by said long arm 34'', and has its right hand end connected by the spring 42 with the stud 43 fixed in said casing 1, and continually tending to stress said roller lever downward. Said lever 40 carries the roller 45 in cooperative relation with the oppositely downwardly inclined top surface of the rocker cam 46, which is fulcrumed on the stud 47 fixed in said main casing 1 and has its rocking movement limited by the stationary stop studs 48 and 49 fixed in said casing 1. The link 50, which is pivotally connected at its right hand end with said rocker cam 46, has its left hand end pivotally connected with the valve rod 31^b to thrust the valve 31' open when the cam roller lever 40 is in the position shown in Fig. I. In that position; the stress of the spring 38 has turned the bell crank lever 34 clockwise, causing said roller 45 to ride over the top crest of the rocker cam 46 into engagement with the incline at the right hand side of the cam; simultaneously forcing the diaphragm 4 downwardly and expelling the air from the chamber 2 through said vent 32 in the valve casing 30 to the atmosphere.

However, when the high pressure air from the

supply conduit 6 forces the diaphragm 5 upward and turns the bell crank lever 11 clockwise against the stress of the spring 15, the exhaust valve 30' is permitted to be closed by its spring 30^a to stop the escape of air through the vent 32 in the valve casing 30 and, simultaneously, the valve 29' is opened by the thrust of the long arm 11'' of the bell crank lever 11 against its stem 29^b to again raise the diaphragm 4 in the first diaphragm chamber 2 and turn the bell crank lever 34 counterclockwise against the stress of its spring 38; thus causing the roller 45 to ride over the crest of the rocker cam 46 into cooperative engagement with the left hand incline at the upward end of the cam, whereupon the stress of the spring 42 turns the rocker cam 46 clockwise and permits the spring 31^a of the valve 31' to close it and stop the flow of high pressure air into the diaphragm chamber 3 and service conduit 8.

However, as above noted, Fig. I shows the position of the parts with the main valve 31' opened, but immediately before the diaphragm 5 has been uplifted to turn the bell crank lever 11 clockwise at the initiation of a pulsation of pressure caused by a reduction of pressure in the service conduit 8 below that for which the spring 15 has been adjusted. That is also the position of the parts shown in Fig. I, when the supply conduit 6 and service conduit 8 are disconnected respectively from the source of supply of compressed air and the receiver to be charged.

Referring to Fig. III; timer valve 28' is a tube mounted to loosely reciprocate to and from its annular seat around the port 28^a in the top of the tubular bushing 28^b, which is stationary in the timer valve casing 28. The sudden inflow of high pressure air to diaphragm chamber 3, when the main valve 31' is opened, lifts valve 28' against its seat and reduces the effective area of port 28^a. When such inflow stops, valve 28' falls onto the stationary tubular abutment plug 28^c, and the effective area of port 28^a is increased. Thus timer valve 28' differentially restricts the passage of air to and from the second diaphragm chamber 3, and automatically determines the times when the first and second control valves, 29' and 30', shall be alternately opened and closed.

When the supply conduit 6 is connected with a source of highly compressed air and the service conduit 8 closed at its discharge end by the chuck valve, or any other means, both the diaphragm chambers 2 and 3 are charged with the high pressure air, uplifting the diaphragms 4 and 5 and turning the bell crank levers 11 and 34 to the limit of their movement respectively clockwise and counterclockwise. Such movement of the lever 11 is limited by contact of its arm 11'' with the inner face of the right hand side wall of the casing 1. Such movement of the lever 34 is limited by the stop screw 51 which is axially adjustable in the arm 34'' of that lever and may be set in adjusted position by the nut 52 thereon. Said screw 51 encounters the inner face of the left hand wall of said casing 1. Such movement of the lever 34 causes the roller 45 to pass over the crest of the cam 46 into engagement with the left hand incline of said cam; so that the spring 42, continually stressing the right hand end of the lever 40 downwardly, causes the cam 46 to rock clockwise against the stop 48, withdrawing the valve rod 31^b from the main valve casing 31, and permitting the main valve 31' to be closed by its spring 31^a.

Both the supply conduit 6 and the service con-

duit 8 being charged with highly compressed air, and the stress of the spring 15 being adjusted to the pressure desired in a receiver, for instance a vehicle tire; connection of the chuck valve at the discharge end of the service conduit with the tire valve stem permits the high pressure air in the conduit 8 to escape into the tire until the pressure in the tire and in the service conduit is equalized, by decrement of the pressure in the conduit 8 and increment of the pressure in the tire. The decrement of pressure in the diaphragm chamber 3 beneath the diaphragm 5 permits the spring 15 to turn the lever 11 counterclockwise with the effect of thrusting open the valve 30' by the rod 30^b of that valve, thus permitting the escape of the high pressure air from the diaphragm chamber 2 beneath the diaphragm 4, backward through the air supply conduit branch 6^a and valve casing 30, and the vent opening 32 in the valve casing 30 to the atmosphere. Such venting of the diaphragm chamber 2 permits the spring 38 to turn the lever 34 clockwise to the position shown in Fig. I, with the effect of forcing the roller 45 over the crest of the cam 46 to the right hand side thereof and permitting the spring 42 to rock the cam 46 counterclockwise to the position shown in Fig. I and thereby open the main valve 31' to admit a pulsatory charge of highly compressed air to both diaphragm chamber 3 and the service conduit 8.

When pressure in the diaphragm chamber 3, beneath the diaphragm 5, rises to a degree sufficient to overcome the effective forces of the spring 15, the arm 11'' is moved clockwise. Such clockwise movement of the arm 11'' permits the spring 30^a to move the valve 30' to closed position, thereby preventing the further exhausting of the chamber 2 to atmosphere. Clockwise movement of said arm 11'' also opens the valve 28' to permit the flow of high pressure air to the chamber 2 beneath the diaphragm 4. When pressure in the diaphragm chamber 4 rises to a degree sufficient to overcome the effective forces of the spring 38, the arm 34'' is moved counterclockwise. Such counterclockwise movement of the arm 34'' causes the roller 45 to roll up the right hand inclined surface of the cam 46 and roll down the left hand inclined surface, thereby moving said cam clockwise. Such clockwise movement of the cam 46 moves the link 50 and the rod 31^b to the right, thereby permitting the main valve 31' to be closed by its spring 31^a, thus shutting off the supply of high pressure air both to the chamber 3 and the service conduit 8.

Such pulsatory charges are automatically effected in succession until the pressure in the tire or other receiver equals the pressure to which the spring 15 has been adjustably set. Thereupon, disconnection of the service conduit 8 from the tire permits the chuck valve to close and trap the highly compressed air from the source in the diaphragm chambers 2 and 3 and service conduit 8, ready for the initiation of another dispensing operation by permitting the highly compressed air to escape from the discharge end of the service conduit 8, as above described.

I have found it convenient to support the valve casings 28 and 30 exterior to the main casing 1, by forming the latter of cast metal and providing it with vertical flanges 53 and 54 in unitary relation. However, they may be otherwise arranged.

Therefore, I do not desire to limit myself to the precise details of construction, arrangement, or method of operation herein set forth, as it is

obvious that various modifications may be made therein without departing from the essential features of my invention, as defined in the appended claims.

I claim:

1. In fluid dispensing apparatus, the combination with a casing enclosing a first diaphragm chamber and a second diaphragm chamber, each containing pressure sensitive means including a reciprocating diaphragm; of a fluid pressure supply conduit having two branches, respectively leading to said chambers; a fluid pressure service conduit leading from the second chamber and arranged to be connected to means at the discharge end of said service conduit adapted for connection to a receiver; respective springs opposed to the fluid pressure on said diaphragms; means for adjustably varying the pressure of the spring opposed to the service pressure diaphragm in the second chamber; a first valve arranged to control the supply of high pressure fluid to the first chamber, a second valve arranged to control the exhaust of fluid from the first chamber to the atmosphere; a main valve arranged to control the supply of high pressure fluid to the second chamber and the service conduit, a timer valve arranged to differentially restrict the passage of fluid to and from the second chamber; means operatively connecting said first and second valves with the diaphragm in said second chamber, and the spring opposed to that diaphragm; whereby said first valve is arranged to be closed and the second valve opened by the stress of the spring opposed to the second diaphragm and the first valve opened and second valve closed, by fluid pressure on that diaphragm; means operatively connecting said main valve with the diaphragm in said first chamber and the spring opposed to that diaphragm; whereby the main valve is arranged to be opened by spring stress, and closed by fluid pressure in said first chamber; whereby said valves are automatically operated in accordance with fluctuations in the fluid pressure on both diaphragms and fluid is dispensed, in successive pulsations, from said supply conduit through said service conduit, until the pressure in the receiver is equal to the effective pressure of the adjusted spring.

2. Apparatus as in claim 1; wherein the control valves have respective springs continually stressing them toward their closed position, the means operatively connecting the main valve with the diaphragm in the first chamber and the spring opposed to that diaphragm includes a bell crank lever, having a short arm in cooperative relation with that diaphragm and a long arm in cooperative relation with the latter spring, a rocker cam, a cam roller lever carrying a roller and pivoted at one end to said long arm, a spring continually stressing the cam roller lever with its roller in cooperative relation with the cam, and a valve push rod in operating relation with said rocker cam.

3. Apparatus as in claim 1; wherein the control valves have respective springs continually stressing them toward their closed position, the means operatively connecting the first and second valves with the diaphragm in the second chamber and the adjustable spring opposed to that diaphragm includes a bell crank lever, having a short arm in cooperative relation with that diaphragm and a long arm in cooperative relation with that spring; and valve push rods in cooperative relation with said long arm; whereby, said

valves are alternately opened and permitted to close, by oscillation of said lever.

4. Apparatus as in claim 1; wherein the means operatively connecting the main valve with the diaphragm in the first chamber and the spring opposed to that diaphragm includes a bell crank lever, having a short arm in cooperative relation with that diaphragm and a long arm in cooperative relation with that spring, a rocker cam, a cam roller lever carrying a roller and pivoted at one end to said long arm, a spring continually stressing the cam roller lever with its roller in cooperative relation with the cam, a valve push rod in operating relation with said rocker cam; the control valves have respective springs continually stressing them toward their closed position, the means operatively connecting the first and second valves with the diaphragm in the second chamber and the adjustable spring opposed to that diaphragm includes a bell crank lever, having a short arm in cooperative relation with that diaphragm and a long arm in cooperative relation with the latter spring, valve push rods in cooperative relation with said long arm; whereby, said valves are alternately opened and permitted to close, by oscillation of said lever.

5. In fluid dispensing apparatus, the combination with a main casing enclosing a first diaphragm chamber and a second diaphragm chamber, each containing pressure sensitive means including a reciprocating diaphragm; of a fluid pressure supply conduit having two branches, respectively leading to said chambers; a fluid pressure service conduit leading from the second chamber and arranged to be connected to means at the discharge end of said service conduit adapted for connection to a receiver; respective springs opposed to the fluid pressure on said diaphragms; means for adjustably varying the pressure of the spring opposed to the service pressure diaphragm in the second chamber; a first valve arranged to control the supply of high pressure fluid to the first chamber, a second valve arranged to control the exhaust of fluid from the first chamber to the atmosphere; a main valve arranged to control the supply of high pressure fluid to the second chamber and the service conduit, a timer valve arranged to differentially restrict the passage of fluid to and from the second chamber; means operatively connecting said first and second valves with the diaphragm in said second chamber, and the spring opposed to that diaphragm, including a lever; whereby said first valve is arranged to be closed and the second valve opened by the stress of the spring opposed to the second diaphragm and the first valve opened and second valve closed, by fluid pressure on that diaphragm; means operatively connecting said main valve with the diaphragm in said first chamber and the spring opposed to that diaphragm; whereby the main valve is arranged to be opened by spring stress, and closed by fluid pressure in said first chamber; whereby said valves are automatically operated in accordance with fluctuations in the fluid pressure on both diaphragms and fluid is dispensed, in successive pulsations, from said supply conduit through said service conduit, until the pressure in the receiver is equal to the effective pressure of the adjusted spring.

6. In fluid dispensing apparatus, the combination with a casing enclosing a first diaphragm chamber and a second diaphragm chamber, each containing pressure sensitive means including a reciprocating diaphragm; of a fluid pressure sup-

ply conduit having branches respectively leading to said chambers; a first valve controlling the supply of high pressure air to the first chamber; a second valve controlling the escape of air from the first chamber through a vent to the atmosphere; a main valve controlling the supply of high pressure air to the second chamber; a fluid pressure service conduit leading from the second chamber and arranged to be connected to means at the discharge end of said service conduit adapted for connection to a fluid receiver; wherein the means connecting the first and second valves with the diaphragm in the second diaphragm chamber includes a lever; and the means connecting the main valve with the diaphragm in the first diaphragm chamber includes a lever.

7. In fluid dispensing apparatus, the combination with a casing enclosing a first diaphragm chamber and a second diaphragm chamber, each containing pressure sensitive means including a reciprocating diaphragm; of a fluid pressure supply conduit having branches respectively leading to said chambers; a first valve controlling the supply of high pressure air to the first chamber; a second valve controlling the escape of air from the first chamber through a vent to the atmosphere; a main valve controlling the supply of high pressure air to the second chamber; a fluid pressure service conduit leading from the second chamber and arranged to be connected to means at the discharge end of said service conduit adapted for connection to a fluid receiver; where-

in the means connecting the first and second valves with the diaphragm in the second diaphragm chamber includes a lever; and the means connecting the main valve with the diaphragm in the first diaphragm chamber includes a rocker cam and two levers.

8. In fluid dispensing apparatus, the combination with a casing enclosing a first diaphragm chamber and a second diaphragm chamber, each containing pressure sensitive means including a reciprocating diaphragm; of a fluid pressure supply conduit having branches respectively leading to said chambers; a first valve controlling the supply of high pressure air to the first chamber; a second valve controlling the escape of air from the first chamber through a vent to the atmosphere; a main valve controlling the supply of high pressure air to the second chamber; a fluid pressure service conduit leading from the second chamber and arranged to be connected to means at the discharge end of said service conduit adapted for connection to a fluid receiver; wherein the means connecting the first and second valves with the diaphragm in the second diaphragm chamber includes a lever; and the means connecting the main valve with the diaphragm in the first diaphragm chamber includes a bell crank lever, a rocker cam, and a cam roller lever, carrying a roller, and a spring continually stressing said roller in cooperative relation with said cam.

VIRGIL D. BARKER.
